UNITED STATES PATENT OFFICE.

JOHN L. STERLING, OF BELLEROSE, NEW YORK.

DESIGN FOR A RADIOTABLE.

Application filed December 13, 1928. Serial No. 29,250. Term of patent 7 years.

To all whom it may concern:

Be it known that I, JOHN L. STERLING, a citizen of the United States, residing at Belleroose, in the county of Nassau and State of New York, have invented a new, original, and ornamental Design for Radiotable, of which the following is a specification, reference being had to the accompanying drawing, forming part thereof.

Fig. 1 is a front elevation of the radio table showing the radio set.

Fig. 2 is a side elevation of a radio table showing a grille for a sound reproducing member.

I claim:

The ornamental design for a radiotable, as shown.

JOHN L. STERLING.
